UNITED STATES PATENT OFFICE.

ELLERY CARROLL, OF MORROW, OHIO.

SHOCK-LOADER.

SPECIFICATION forming part of Letters Patent No. 752,140, dated February 16, 1904.

Application filed June 22, 1903. Serial No. 162,584. (No model.).

To all whom it may concern:

Be it known that I, ELLERY CARROLL, a citizen of the United States, residing at Morrow, in the county of Warren and State of Ohio, 5 have invented certain new and useful Improvements in Shock-Loaders, of which the following is a specification.

This invention appertains to apparatus designed most especially for loading shocks of grain into an ordinary farm-wagon, the mechanism being of such construction as to utilize the draft for elevating the load to a proper height, after which the load may be swung by manual operation to a position over the wagon 15 to be discharged therein.

For a full description of the invention and the merits thereof and also to acquire a knowledge of the details of construction of the means for effecting the result reference is to be had to 20 the following description and drawings here- to attached.

While the essential and characteristic features of the invention are susceptible of modification, still the preferred embodiment of the 25 invention is illustrated in the accompanying drawings, in which—

Figure 1 is a perspective view of a shock-loader embodying the invention. Fig. 2 is a side view thereof. Fig. 3 is a rear view. Fig. 30 4 is a detail view of the snap for securing the hoisting-rope after the same has been passed around the shock or load.

Corresponding and like parts are referred to in the following description and indicated 35 in all the views of the drawings by the same reference characters.

The apparatus is of the nature of an attachment and is adapted to be connected to a farm-wagon in any convenient and substantial way, 40 so as to deposit the load therein.

In its simplest form the shock-holder comprises a coupling-pole 1, axle 2, frame 3, and crane 4, the latter being mounted so as to swing about a vertical axis and operable by 45 means of a lever 5, secured to the post 6 in any substantial manner. To steady the crane, upright 7 is provided and secured at its lower end to the frame and braced at its upper end by means of stay-rods 8, connected at their 50 lower ends to the frame 3 about as indicated.

The axle 2 is loosely mounted in bearings 9 at the outer end of the frame 3 and is provided with ground-wheels 10, which impart rotary movement to the axle as the load is drawn over the field.

A drum 11 is loosely mounted upon the axle 2 and is movable thereon by means of shipper-lever 12, having a forked end to embrace the annularly-grooved end portion of the drum. A hand-latch 13, applied to the lever 12, co-operates with a toothed segment 14 to hold the shipper-lever in an adjusted position. A half-clutch 15 is provided at one end of the drum and is adapted to co-operate with a companion half-clutch 16, secured to the axle 2. 55 Hence when the drum is shifted to the left or moved outward upon the axle and the half-clutches 15 and 16 are brought into engagement the drum is caused to rotate with the axle. A half-clutch 17 is applied to the opposite end of the drum and co-operates with a corresponding half-clutch 18, secured to the frame, whereby upon moving the drum inward or to the right upon the axle 2, so as to bring the clutch elements 17 and 18 into engagement, the drum 11 is held stationary. 60

The hoisting-rope 19 passes over guide-pulleys 20, applied to opposite end portions of the arms of the crane, and one end is secured to the drum 11 and is adapted to wind thereon, and the opposite end is provided with securing means for attachment thereof to the load or shock. The attaching device consists of a frame 21, provided with a fixed hook 22, sheave-pulley 23, pivoted hook 24, and spring-actuated lock-lever 25, the latter being slidably mounted in an extension of the frame 21 and adapted to pass under the inner end of the pivoted hook 24 to hold it closed upon the rigid hook 22 when the ring 26, applied to the end 85 of the hoisting-rope 19, is engaged with the hooks 22 and 24. 90

The loader being coupled to a farm-wagon 27 in any manner, so as to move therewith over the field, and the drum 11 moved to an intermediate position and secured by the latch 13 and segment 14, the apparatus is moved to the shock or load through the instrumentality of the team applied to the farm-wagon. The hoisting-rope 19 is secured to the shock or load 100

by having its loose end portion passed around the shock and engaged with the hooks 22 and 24 and secured by shooting the lock-lever 25 forward beneath the inner end of the pivoted hook 24. The shipper-lever 12 is now operated to move the drum 11 to the left to bring the clutch elements 15 and 16 into engagement, and upon driving the team forward the drum 11 is rotated in the manner stated and winds the hoisting-rope 19 thereon sufficiently to elevate the shock or load to the required point, when the lever 12 is operated to move the drum inward or to the right, so as to bring the clutch elements 17 and 18 into engagement, thereby holding the shock in suspension. The crane is now swung by means of the lever 5 so as to bring the sheek or load over the wagon, and the lever 12 is operated to move the drum 11 to an intermediate point, when the weight of the shock will unwind the rope from the drum and permit the load to drop into the wagon, when the hoisting-rope is disconnected therefrom and the apparatus ready for repetition of the operation for depositing additional shocks or loads into the wagon.

Having thus described the invention, what is claimed as new is—

1. In a loader of the character described, the combination of an axle adapted to be rotated by traction of its wheels with the ground, a swinging crane, a hoisting-rope, a drum having the hoisting-rope connected thereto so as

to wind thereon, coöperating means between the axle and drum to cause simultaneous rotation thereof to effect a lifting of the load by movement of the apparatus over the field, coöperating means between the frame of the loader and the drum to hold the load in suspension, and means for moving the drum to any one of its three positions, substantially as described.

2. In a shocck-loader, the combination of an axle adapted to be rotated through traction of its wheels with the ground, a drum loosely mounted upon the axle, means coöperating with the drum, the frame and the axle for connecting said drum to either the axle or the frame, a hoisting-rope having one end secured to the drum and adapted to wind thereon, a swinging crane supporting said hoisting-rope, and securing means at the outer end of the hoisting-rope consisting of a ring at the extremity of the hoisting-rope, a frame having a sheave-pulley loosely mounted upon the hoisting-rope, and a rigid hook, a pivoted hook and a spring-actuated lock-lever applied to said frame and coöperating substantially in the manner set forth for the purpose specified.

In testimony whereof I affix my signature in presence of two witnesses.

ELLERY CARROLL. [L. S.]
